UNITED STATES PATENT OFFICE

CHARLES R. HULTGREEN, OF CHICAGO, ILLINOIS, ASSIGNOR TO S. KARPEN & BROS., OF CHICAGO, ILLINOIS, A CORPORATION OF WEST VIRGINIA

ADJUSTABLE-BACK CHAIR, ETC.

Application filed December 20, 1926. Serial No. 155,921.

This invention relates particularly to adjustable-back chairs, or the like; and the primary object is to provide an article of this character with improved adjusting means for the back.

The invention is illustrated in the accompanying drawings as embodied in a seat, or chair, adapted to be used in automobiles, motor busses, etc. It is to be understood, however, that the invention is applicable, generally, to chairs, or seats, provided with adjustable backs.

In the drawings—

Fig. 1 is a side elevational view of a chair constructed in accordance with the invention; Fig. 2, a rear elevational view of the same; Fig. 3, a sectional view taken as indicated at line 3 of Fig. 2; Fig. 4, an enlarged broken sectional view taken as indicated at line 4—4 of Fig. 5 and showing the hinge connections between the adjustable back and the chair-body and showing also a portion of the co-acting cam device; and Fig. 5, a section taken as indicated at line 5 of Fig. 4.

In the illustration given, A designates the frame of the chair; B, a pivotally mounted back; C, a cam device co-acting with the pivot-members of the back; and D, a cam-releasing device.

The frame A may be of any suitable construction. In the illustration given, it comprises a seat-frame 1 mounted on front legs 2 and rear legs 3. The seat-frame is shown as supporting a cushion 4.

The back B may be of any suitable construction. In the illustration given, it is shown as comprising a tubular U-shaped frame-member 5 whose arms are equipped at their lower extremities with barrel-shaped pivot-members 5^a, and a cushion 5^b secured by the frame 5 in any suitable manner.

The rear legs 3 of the chair frame preferably are provided with upward extensions 3^a which afford supports for pivot-pins 6.

The barrel 5^a, in each case, is open at its outer side, and the free edge of the peripheral wall of the barrel bears against the inner surface of the plate-like extension 3^a. The peripheral portion, or flange, of the member 5^a is provided with a lug 7 which engages

a segmental slot 8 with which the upper edge of the supporting member 3^a is provided. Within the barrel 5^a and forming a closure for its open outer side is a disk 9 equipped with a peripheral flange 9^a which affords a bearing for the inner surface of the peripheral portion of the barrel 5^a. The disk 9 is disposed adjacent the extension 3^a and is secured thereto by a rivet 10 which has an extension 10^a extending into the barrel. This extension serves as a stud with which is connected one end of a coil-spring 11 which extends about a pulley 12 mounted on the pivot 6. The spring extends into the hollow arm of the back-frame 5, and is secured by means of a stud 13. It will be understood that the construction described preferably is duplicated at the two points of pivotal connection between the chair-back and the main frame.

The eccentric device C serves as a locking device for the chair-back. The device preferably comprises a cam-disk 14 associated with each of the barrel-like pivot-members 5^a of the chair-back, these disks being eccentrically mounted upon pivot-studs 14^a carried by the rear legs 3 of the chair-frame; arms 14^b depending from the eccentric disks; and a cross-rod 14^c connecting the lower extremities of the arms. In effect, the eccentric disks constitute the end-portions of the arms of a yoke. The peripheral surfaces of the disks preferably are knurled, as indicated in Fig. 5. The eccentrics are held in position with the peripheral surfaces of the pivot-barrels 5^a by means of springs 15 which extend rearwardly from the arms and are connected with the chair-legs 3. Thus, the springs tend to rotate the eccentric disks in a direction to grip the pivot-barrels 5^a of the chair-back. This gripping action is augmented by any rearward pressure upon the chair-back. It will be understood that the gripping of the pivot-barrels by the eccentrics may be relieved by swinging the arms 14^b forwardly, as viewed in Fig. 3. The releasing action may be effected by means of a lever 16 which is pivotally connected at 16^a with one of the rear chair-legs. This lever is shown of angular form, and is provided at the elbow-portion with a stud 16^b which engages the adjacent

95
100

5 arm 14^b. The forwardly turned extremity of the lever has connected therewith a rod 16^c which is slidable through an eye 17 attached to one of the arms 18 with which the chair-frame is equipped. The upper end of the rod 16^c terminates in a ring 16^d which is conveniently located near the front portion of the chair-arm.

10 The operation will be readily understood. The eccentrics 14 are normally held in gripping engagement with the pivot-barrels 5^a of the chair-back, as shown in Fig. 3. Any backward pressure upon the chair-back tends to rotate the eccentric disks counter-clockwise, as viewed in Fig. 3, thus increasing the gripping action. When desired, the rod 16^c may be lifted to cause the yoke comprising the arms 14^b and cross-rod 14^e to be swung forward, thereby releasing the eccentric disks 15 from the pivot-barrels 5^a.

20 The springs 11 tend to swing the chair-back forwardly. If desired, the springs may be of sufficient strength to cause the chair-back to follow the person when the occupant leans forwardly in the chair, even without the necessity of operating the release device. On the other hand, the springs may be of suitable tension to effect the forward swing of the chair-back only upon release of the eccentric disks 25 through the medium of the releasing device D. In any event, the device D affords a means of effecting positive release of the eccentric disks, if desired, or necessary. The chair-back may be swung forwardly by exerting a small forward pressure at the upper end of the back, even without the use of the springs 11 and without the use of the release device D. On the other hand, any rearward pressure upon the chair-back when the eccentric disks are in gripping engagement with the members 5^a serves only to increase the gripping effect and prevent the rearward swing of the chair-back. It will be seen, therefore, that when the chair-back is to 30 be swung rearwardly, this can be effected only after operating the releasing device D so that the eccentric disks will be held out of gripping engagement during the rearward swing of the back. The stop-lugs 7 working in the 35 segmental slots 8 permit such movements of the back as are desirable, but prevent undue movement of the back.

40 The foregoing detailed description has been given for clearness of understanding only, and no unnecessary limitations should be understood therefrom, but the appended claims should be construed as broadly as permissible.

45 What I regard as new, and desire to secure by Letters Patent, is:

50 1. In combination with a frame adapted to support a seat, a swinging back having a pivot-member rigidly connected therewith, an eccentric frictional gripping device coacting with said pivot-member, means yielding-

ly holding said eccentric device in locking-grip engagement with said pivot-member, and means for releasing said eccentric member from gripping engagement with said pivot-member.

55 2. In combination, a chair-frame, a back pivotally mounted on said frame and equipped with gripping-disks extending beneath the pivot-axis, a yoke equipped with gripping-disks eccentrically mounted on pivots carried by said frame, yielding means tending to throw said eccentrically mounted gripping-disks into engagement with said first-named gripping-disks, and releasing means associated with said yoke, said releasing means having an actuating member located at one side of the chair-frame.

60 3. A chair comprising a frame provided with pivot-supports, a back equipped with barrel-form pivot-members connected with said supports, pivot-studs carried by said frame beneath said pivot-members, a yoke equipped with disks eccentrically mounted on said pivot-studs, a spring connected to said yoke and tending to swing said yoke rearwardly and carry said disks into gripping engagement with said pivot-members, and a releasing device associated with said yoke.

65 4. A chair comprising a frame provided with pivot-supports, a back equipped with barrel-form pivot-members connected with said supports, pivot-studs carried by said frame beneath said pivot-members, a yoke equipped with disks eccentrically mounted rigidly on said pivot-studs, a spring connected to said yoke and tending to swing said yoke rearwardly and carry said disks into gripping engagement with said pivot-members, and a releasing device associated with said yoke, said releasing device comprising a lever equipped with means for engaging said yoke, and a rod extending upwardly and forwardly from said lever.

70 5. A chair comprising a frame provided with pivot-supports, a back equipped with barrel-form pivot-members, pivots connecting said pivot-members to said pivot-supports, pulleys mounted on said pivots, coil-springs mounted on said pulleys and connected at one end to the pivot-supports and at the other end to said back, a yoke equipped with rigidly connected disks eccentrically mounted on pivots carried by said frame at points below said pivot-members, yielding means tending to throw said eccentrically mounted gripping-disks into engagement with said barrel-form pivot-members, and a releasing device associated with said yoke.
